CARRIER SCRAPER

John W. Zahara, San Carlos, Calif.

Application June 24, 1941, Serial No. 399,487

13 Claims. (Cl. 37—126)

The present invention relates to carrier scrapers of the heavy duty road grader type employed in construction work of all kinds wherein movement of earth is desired. More specifically my invention relates to earth movers utilizing main and auxiliary bowls.

One of the principal objects of the invention is the improvement and simplification of the means employed to move relatively the main and auxiliary bowls in the loading and dumping operations.

The invention also relates to improvements in means for insuring the return of the main bowl from its discharge to loading position.

Additionally, the invention forming the subject-matter of this application contemplates certain novelties in construction whereby the means for actuating the auxiliary bowl, or apron as it is termed by some in the art, are so positioned as to reduce wear and tear thereon to a minimum and to thus effect certain desirable economies in the operation of the devices.

Other objects and advantages will become apparent as this specification proceeds and the novelty of the invention will be set forth in the appended claims.

In the drawings forming a part thereof:

Fig. 1 is a side elevation of a carrier scraper embodying my invention with the main and auxiliary bowls in a carrying or loaded position,

Fig. 2 is a vertical longitudinal section of the device of Fig. 1 with the main and auxiliary bowls in discharge position.

Fig. 3 is a vertical longitudinal section of the device of Fig. 1 showing the bowls in scraping position,

Fig. 4 is a longitudinal sectional view along the line 4—4 of Fig. 1, and

Fig. 5 is a section along the line 5—5 of Fig. 4.

The preferred embodiment of my invention illustrated in the drawings includes the essential elements of a carrier scraper of a well-known type. The numeral 10 denotes the side frames of the scraper of conventional trussed beam construction at the rear end of which the vehicle is supported by the usual transversely spaced wheel units 11.

A pair of elongated beams 12, pivotally connected at one end to the side frames 10 by trunnions 13 positioned toward the rear of the frames 10, converge at their forward ends in the form of a neck for connection to the conventional swivelled front wheels (not shown). The forward end of the scraper is supported by a pull cable 14, anchored at the end of the side frame

as at 15, passing over a sheave 16 disposed on the beams 12 and taken up by a conventional power drum on the tractor by which the scraper is drawn (not shown). Thus the forward end of the scraper is not only supported by the combination of the beam 12 and the cable 14, but by these means may be raised and lowered between scraping and carrying positions (see Figs. 3 and 1, respectively).

10 Additionally, the scraper includes side plates 18 rigidly secured to the side frames 10 to define the sides of the compartment into which the earth is gathered by the scraper means, which side plates in this instance extend below the side frames 10 to provide a skirt 19. The main bowl 20, as usual, is a scoop shaped body, which in the loading and carrying operations forms the bottom and back of the earth compartment, and is connected for pivotal movement at its forward end to a pin 21 extending transversely between and suitably journaled in the side skirts 19. A post 22 disposed medially of the back of the main bowl 20 extends upwardly therefrom in the form of a gooseneck 23.

15 25 The main bowl 20 is rendered tiltable on its pivot 21 by means of its operative connection to a pull cable 27 passing through a plurality of sheaves 28 and 29, the former being carried at the outer end of gooseneck 23 and the latter being positioned on a beam 30 spanning a pair of posts 31 extending upwardly from the side frames 10 at the forward end of scraper. The posts 31 are braced by the rearwardly declining struts 32 connected at their opposite ends to a pair of shorter posts 33 extending upwardly from frame 10 midway the sides of the scraper.

20 25 As will be noted from Fig. 1 one end of the pull cable 27 is anchored on the conventional block for sheaves 29. The opposite end extends to a suitable power drum on the tractor (not shown). It will therefore be apparent that pull exerted on cable 27 will tend to shorten the distance between sheaves 28 and 29 and thus tilt main bowl 20 on its pivot 21 to effect discharge of the contents of the scraper, whereas slackening off on the cable 27 will permit bowl 20 to return to its scraping position, such return being aided and insured by certain novel means presently to be described.

25 30 A scraper blade 35 having a rigid support 36 extends transversely between the skirts 19 with its cutting edge projecting slightly below the edge of the said skirts. If desired the parallel pin 21 may be additionally journaled on the blade support 36 for additional strength in the structure.

It will be readily appreciated that the blade may be provided with an adjustable connection to the support 36 to meet varying conditions.

An auxiliary bowl or front apron 40 is supported for relative pivotal movement with respect to the main bowl 20 by a pair of rigidly connected rearwardly projecting arms 41, the ends of which are connected to trunnions 42 in lugs 43 on the posts 33.

The auxiliary bowl 40 is automatically moved from a closed position, in which its lowermost edge abuts the blade 35 (see Fig. 1) to its full open or raised position (see Fig. 2) upon the tilting of the main bowl 20. The means for effecting this automatic opening and closing of the auxiliary bowl 40 include links 44 connected at one end to the auxiliary bowl 40 and having an operative connection with pusher rods 45 slidably disposed on the side members of frame 10 and extending through the posts 33. Blocks 48 on the rearmost ends of pusher rods 45 carry sheaves 49 through which cable 50 is passed to provide an operative connection whereby pull exerted on the cable 50 will cause the pusher rods 45 to be moved forwardly to urge auxiliary bowl 20 upwardly about its pivots 42 into its opened position.

The two ends of cable 50 are anchored, as at 51, on post 22 on main bowl 20, from whence cable 50 extends through sheaves 52 in blocks 53 located on the top and either end of the compression spring housing 54 at the rear of the scraper. From sheaves 52 cable 50 extends through sheaves 55 in blocks 56 on the side frames 10 adjacent posts 33 and from thence over sheaves 49 back to sheaves 57 in blocks 53 and into the compression spring box 54 (see Fig. 4). By multiplying the number of sheaves 49 and 57 the speed of movement of auxiliary bowl 40 may be decreased for heavy duty operations.

Within the housing 54 there are two longitudinally extending superimposed compression springs 60 the function of which, through the medium of operative connections with cable 50, is to urge the main bowl 20 rearwardly from its full open position (see Fig. 2) past its center of gravity toward its scraping position (see Fig. 3). Opposite ends of the springs 60 are anchored to the end walls of the housing 54, as at 61, and their free ends receive keeper pins 62 projecting from sheave blocks 63. As will be noted from Fig. 4 cable 50 is looped about sheaves 64 on blocks 63, passing out of the spring box 54 over sheaves 65 and 66 positioned at opposite ends of the housing 54.

Normally blocks 63 are locked against longitudinal movement in the housing 54, and hence springs 60 are retained against compression, by dogs 67 the tips of which engage the projecting lips 68 on blocks 63. Release of the dogs 67 is effected when blocks 48, under the pull of cable 50 on sheaves 49, are moved forwardly to strike the triggers 69 slidably supported on stops 70 on frame 10. Movement of triggers 69 causes rods 71, with which they are connected, to be drawn forwardly moving the inclined surfaces 72, at the opposite ends of the rods 71, under and urging upwardly the wedge pins 73. Wedge pins 73 are slidably retained by any suitable guide means, such as straps (not shown). Dogs 67, normally urged into engagement with blocks 63 by springs 74, are likewise provided with an inclined surface 75 against which the upward thrust of wedge pins 73 will be transmitted into lateral movement of the dogs 67 out of engagement with sheave

blocks 63 compressing springs 74. When dogs 67 are thus retracted further pull on cable 50, as main bowl 20 moves toward its dumping position, will draw the sheave blocks toward each other and compress the springs 60 for the purpose above stated.

While in the preferred form of the invention I have illustrated a wedge type dog release it will be readily appreciated by those skilled in the art that other means may be substituted with equal efficacy. There are many ways in which triggers 69 and dogs 67 may be linked for conjoint movement.

Operation

To set the machine for the loading operation, i. e., scraping, the operator takes up cable 27 on the tractor power drum to raise the main bowl 20 sufficiently to cause a pull on cable 50. Since both ends of cable 50 are anchored on post 22 this initial movement will draw sheave blocks 48 toward the stops 70 and urge pusher rods 45 forwardly which, through the links 44, will swing auxiliary bowl 40 about its pivot 42. This movement of auxiliary bowl 40 need be very slight since only a relatively narrow slot or opening between its bottom edge and blade 35 is necessary to effectively load the scraper (see Fig. 3). In practice the earth passing over blade 35 under the momentum of the vehicle coming from the bottom surges within the compartment to fill both main and auxiliary bowls.

When the scraper is fully loaded the operator takes up cable 14 on the power drum at the tractor to raise the carrier clear of the earth line, at the same time slackening off on cable 27 to permit the weight of the load to lower the main bowl 20 to its carrying position and move the auxiliary bowl 40 into its closed position abutting the blade 35 (see Fig. 1).

In the dumping operation the operator is required to merely take up on cable 27 until the main bowl is raised to its full discharge position (see Fig. 2) as the opening of the auxiliary bowl 40 is fully automatic. As main bowl 20 swings upwardly about its pivot 21 cable 50, anchored on post 22, is drawn over sheaves 52, 55, 49 and 57, causing sheave block 48 and pusher rod 45 to slide forwardly and by means of the link 44 urge auxiliary bowl 40 about its pivotal connection 42 to post 33 into full discharge position (see Fig. 2). Blocks 48 at the end of their paths of travel actuate triggers 69 and are checked by stops 70 on the side frame 10, thus limiting further opening of the auxiliary bowl 40.

Actuation of the triggers 69 draws rods 71 forwardly to thrust wedge pins 73 upwardly to disengage the dogs 67 and thus release the sheave blocks 63. Continued movement of the main bowl 20 toward full discharge position draws on cable 50 which in passing over sheaves 64 in the spring box 54 compresses the springs 60. When the load has been discharged cable 27 is slackened off at the power drum and the tension of springs 60 transmitted through cable 50 will pull main bowl 20 past its center of gravity from whence of its own weight it will return toward its lowermost or loading position. Return of rods 71 and resetting of triggers 69 is effected by any yieldable means such as springs 71 connected between the outer ends of the rods 70 and the vehicle frame.

It will be apparent to those skilled in the art that in the device forming the subject-matter hereof provision has been made for minimizing

wear and tear on cables and sheaves and other means for actuating the auxiliary bowl by locating the same away from forward end of the machine at which earth is contacted.

Additionally, the simplified means for automatically actuating the auxiliary bowl and insuring return of the main bowl to its loading position will be found advantageous in that they permit economies in cost of construction and maintenance, while at the same time attaining obvious efficiencies in operation.

Having fully shown and described a preferred embodiment of my invention for purposes of illustration I desire full protection as to the many permissible changes therein which may be made within the scope of the appended claims.

The invention claimed is:

1. A carrier scraper of the type wherein oppositely arranged main and auxiliary bowls are supported by a frame for tilting movement relative to each other from carrying to discharge position comprising means for effecting tilting of the main bowl, members slidably mounted on said frame having operative connections with the auxiliary bowl to cause it to be moved from carrying to discharge position, and means actuated by the main bowl upon tilting thereof to effect movement of the slidable members.

2. A carrier scraper of the type wherein oppositely arranged main and auxiliary bowls are supported by a frame for tilting movement relative to each other from carrying to discharge position comprising means for effecting tilting of the main bowl, members slidably mounted on said frame having operative connections with the auxiliary bowl to cause it to be moved from carrying to discharge position, means actuated by the main bowl upon tilting thereof to effect movement of the slidable members, and stop means for the slidable members.

3. A carrier scraper of the type wherein oppositely arranged main and auxiliary bowls are supported by a frame for tilting movement relative to each other from carrying to discharge position comprising means for effecting tilting of the main bowl, members slidably mounted on said frame, supports therefor, means actuated by the main bowl upon tilting thereof to effect movement of the slidable members, means connecting the slidable members with the auxiliary bowl to cause it to be moved from carrying to discharge position at a rate greater than that of the concomitant movement of the main bowl, and stop means for the slidable members.

4. A carrier scraper of the type wherein oppositely arranged main and auxiliary bowls are supported by a frame for tilting movement relative to each other from carrying to discharge position comprising means for effecting tilting of the main bowl, members slidably mounted on said frame, links connecting the slidable members and the auxiliary bowl, and means actuated by the main bowl upon the tilting thereof to effect movement of the slidable members.

5. A carrier scraper of the type wherein oppositely arranged main and auxiliary bowls are supported by a frame for tilting movement relative to each other from carrying to discharge position comprising means for effecting tilting of the main bowl, members slidably mounted on said frame, pusher rods fixed on the slidable members, links connecting the pusher rods and the auxiliary bowl, and means actuated by the main bowl upon tilting thereof to effect movement of the slidable members.

6. A carrier scraper of the type wherein oppositely arranged main and auxiliary bowls are supported by a frame for tilting movement relative to each other from carrying to discharge position comprising means for effecting tilting of the main bowl, members slidably mounted on said frame, pusher rods fixed on the slidable members, links connecting the pusher rods and the auxiliary bowl, means actuated by the main bowl upon tilting thereof to effect movement of the slidable members, and stop means for the slidable members.

7. A carrier scraper of the type wherein oppositely arranged main and auxiliary bowls are supported by a frame for tilting movement relative to each other from carrying to discharge position comprising means for tilting the main bowl, a pair of members slidably mounted on said frame, means connecting the slidable members and the auxiliary bowl to effect tilting of the latter upon movement of the former, and flexible means having an operative connection with the main bowl and said slidable members to actuate the slidable members upon the tilting of the main bowl.

8. A carrier scraper of the type wherein oppositely arranged main and auxiliary bowls are supported by a frame for tilting movement relative to each other from carrying to discharge position comprising means for tilting the main bowl, a pair of members slidably mounted on said frame, means connecting the slidable members and the auxiliary bowl to effect tilting of the latter upon movement of the former, flexible means having an operative connection with the main bowl and said slidable members to actuate the slidable members upon the tilting of the main bowl, and stop means limiting the movement of the slidable members.

9. A carrier scraper of the type wherein oppositely arranged main and auxiliary bowls are supported by a frame for tilting movement relative to each other from carrying to discharge position comprising means for tilting the main bowl, a pair of members slidably mounted on said frame, means connecting the slidable members and the auxiliary bowl to effect tilting of the latter upon movement of the former, flexible means having an operative connection with the main bowl and said slidable members to actuate the slidable members upon the tilting of the main bowl and yieldable means releasable upon movement of the slidable members a predetermined distance to urge the main bowl from its tilted position back toward its carrying position.

10. A carrier scraper of the type wherein oppositely arranged main and auxiliary bowls are supported by a frame for tilting movement relative to each other from carrying to discharge position comprising means for tilting the main bowl, a pair of members slidably mounted on said frame, means connecting the slidable members and the auxiliary bowl to effect tilting of the latter upon movement of the former, flexible means having an operative connection with the main bowl and said slidable members to actuate the slidable members upon the tilting of the main bowl, compressible members having an operative connection with the said flexible means effective upon compression to urge the main bowl from its tilted position back toward its carrying position, and releasable means normally restraining the compressible members.

11. A carrier scraper of the type wherein oppositely arranged main and auxiliary bowls are

supported by a frame for tilting movement relative to each other from carrying to discharge position comprising means for tilting the main bowl, a pair of members slidably mounted on said frame, means connecting the slidable members and the auxiliary bowl to effect tilting of the latter upon movement of the former, flexible means having an operative connection with the main bowl and said slidable members to actuate the slidable members upon the tilting of the main bowl, compressible members having an operative connection with the said flexible means effective upon compression to urge the main bowl from its tilted position back toward its carrying position, releasable dogs normally restraining the compressible members, and means actuated by the slidable members to effect release of the restraining means for the compressible members.

12. A carrier scraper of the type wherein oppositely arranged main and auxiliary bowls are supported by a frame for tilting movement relative to each other from carrying to discharge position comprising means for tilting the main bowl, a pair of members slidably mounted on said frame, means connecting the slidable members and the auxiliary bowl to effect tilting of the

latter upon movement of the former, flexible means having an operative connection with the main bowl and said slidable members to actuate the slidable members upon the tilting of the main bowl, compressible members having an operative connection with the said flexible means effective upon compression to urge the main bowl from its tilted position back toward its carrying position, releasable dogs normally restraining the compressible members, trigger means in the path of the slidable members having an operative connection to release said dogs.

13. A carrier scraper of the type wherein oppositely arranged main and auxiliary bowls are supported for tilting movement relative to each other from carrying to discharge position comprising means for tilting the main bowl, compressible members having an operative connection with the main bowl effective upon compression to urge the main bowl from its tilted position back toward its carrying position, and releasable means restraining the compressible members through the greater portion of the tilting movement of the main bowl from its carrying to discharge position.

JOHN W. ZAHARA.
